UNITED STATES PATENT OFFICE

160,883

SHIRT OR THE LIKE

Dora A. Pope, Atwood, Colo.

Application October 27, 1948, Serial No. 149,327

Term of patent 7 years

(Cl. D3—25)

To all whom it may concern:

Be it known that I, Dora A. Pope, a citizen of the United States, residing at Atwood, in the county of Logan, and State of Colorado, have invented a new, original, and ornamental Design for a Shirt or the Like, of which the following is a specification, reference being had to the accompanying drawing, forming part thereof and in which:

Fig. 1 is a front view of a shirt showing my new design; and

Fig. 2 is a rear view thereof.

I claim:

The ornamental design for a Shirt or the Like, as shown.

DORA A. POPE.
